UNITED STATES PATENT OFFICE.

EARL L. KOCH, OF PITTSBURGH, PENNSYLVANIA, ASSIGNOR TO FREDERICK S. McCULLOUGH, OF WILKINSBURG, PENNSYLVANIA.

RADIOTUBE AND METHOD OF OPERATING SAME.

Application filed April 25, 1925. Serial No. 25,903.

This invention relates to thermionic tubes, and is for a tube of the equi-potential cathode type wherein the cathode may be energized by an alternating current. 5 The present invention has for its object to provide a thermionic tube in which the cathode may be heated from a source of alternating current without any undesirable hum or distortion resulting from the action 10 of the alternating current field in the tube.

A further object of the invention is to provide a tube capable of use with alternating or pulsating currents which may have superior amplification factors and lower impedance than present types of tubes. 15

Constructions have heretofore been proposed wherein a cathode on a porcelain rod is heated by means of a resistance element disposed above the plane of the grid and the 20 plate of the tube, whereby its field was sufficiently removed from electron flow between the cathode, grid and plate as to have little effect on the action of the tube, thereby substantially eliminating alternating or pulsating 25 current hum.

Such a construction had some disadvantages due to the length of the cathode and heater unit, and removed the source of heat to a point where much of the heat would be 30 radiated before it reached the cathode, particularly the end most remote from such heater. It also resulted in a noticeable temperature gradient along the cathode directly affecting electron emission.

According to the present invention, the 35 heater element may be in close proximity to the emitting portion of the cathode and may extend therethrough without causing undesirable effects.

The invention may be readily understood 40 by reference to the accompanying drawing, wherein:

Fig. 1 is a more or less diagrammatic section through a tube embodying my invention; and

Fig. 2 is a typical circuit diagram for using the tube.

In the drawing, 5 designates a suitable envelope, having a base portion 6 and a lower stem 7. Secured to the base portion of the envelope is a base 8, preferably of standard construction.

In the upper part of the envelope is an

upper stem 9 through which two wires 10 may pass. These wires connect with a resistance heater 10^a extending down through a porcelain or other suitable rod 11. Fitted over this rod is a sleeve 12 comprising the cathode of the tube. A lead wire 13 may extend from this sleeve or cathode through 14 the stem 7 and connect with a contact pin 14 on the base of the tube.

Surrounding that portion of the rod through which the resistance heater 10 passes and out of contact with the cathode, is the 65 input grid 15. A lead wire 16 may connect the input grid with contact pin 17 on the base. At one end of the rod, preferably the lower end, just below the input grid 15, is a small auxiliary grid or auxiliary control electrode 18. This auxiliary grid may connect with a contact pin 19 on the base through a wire 20.

Surrounding the input grid, but out of contact therewith, is the plate or anode 21, 70 which may be of cylindrical or other suitable formation. A lead wire 22 may connect the anode 21 with a contact pin 23 on the base.

In use, the tube functions as any other 80 tube and may be used in any of the usual radio tube circuits, as illustrated in the typical diagram of Fig. 2. The heater lead wires 10 are connected with a suitable source of current, preferably with a house-lighting circuit through a step-down transformer. 85 The circuit shown is a simple regenerative detector circuit, but the invention is not restricted to any particular circuit.

However, in order to eliminate alternating 90 current hum that would otherwise result, a low voltage battery C is put in the circuit between the cathode and the auxiliary grid. This battery has its negative side connected with the auxiliary grid, whereby it puts a negative potential or bias on this grid. This 95 effectively eliminates all alternating current noises.

The theory of the tube, as far as the effect 100 of the auxiliary grid is concerned, is not definitely understood, but tubes embodying this feature have successfully demonstrated the practicability of the invention.

It will be understood that the drawing and description merely disclose one embodiment of the invention, and that various 105 changes in the construction and circuits em-

bodying the invention are contemplated and to be considered as being within the scope and spirit of the appended claims.

What is claimed is:

5. 1. A thermionic tube having an anode, a cathode, a looped resistance heater for the cathode, a helical control electrode, and a helical auxiliary control electrode adjacent one end of the cathode and adjacent the end 10 of the first control electrode, said helical electrodes consisting of different numbers of turns of substantially the same diameter.
  2. A thermionic tube having an anode, a cathode, a looped resistance heater for the cathode extending along the cathode and adapted to be energized by alternating current, a control electrode interposed between the anode and cathode, and an auxiliary control electrode at one end of the first control electrode and separate therefrom.
  3. A thermionic tube having an anode, a cathode, a resistance heater for the cathode, and a plurality of separate helical control electrodes having substantially the same 25 radii and arranged longitudinally of the cathode and extending over distinct areas of the cathode.
  4. A radio tube having an anode, a cathode, a looped resistance heater for the cathode extending therealong, a helical control electrode between the anode and the cathode and extending along the anode out of contact with said cathode and anode, and a helical auxiliary control electrode beyond 30 one end of said first control electrode and separate therefrom.
  5. A radio tube having an anode, a sleeve-like cathode, a porcelain rod extending through the cathode, a looped resistance element within the porcelain rod and within the cathode and adapted to be energized from a source of alternating current, a grid extending throughout the greater portion of the length of the cathode, an auxiliary control 45 electrode at one end of the first grid and separate therefrom, said auxiliary control electrode extending along a portion of the cathode beyond that portion along which the first grid extends, said grid and auxiliary control 50 being interposed between the cathode and the anode.
  6. A thermionic tube having a refractory supporting element therein, a resistance heater extending throughout the greater portion of the length of the refractory supporting element, a sleeve surrounding the refractory supporting element and comprising the cathode of the tube, an anode spaced away from the cathode, a main grid extending 55 along that portion of the cathode which overlies the heater, and an auxiliary grid extending along that portion of the cathode beyond the part that overlies the heater, both of said grids being in the path of the normal electron flow from the cathode to the 60 anode.
  7. A radio tube having an equipotential cathode, a heater for said cathode energized from a source of alternating current, an anode, and a pair of separate control electrodes extending along the cathode and extending along different portions of the length of the cathode, said electrodes consisting of helixes of wire.
  8. A radio tube having a cathode, an 75 anode, a heater for the cathode partially coextensive with the cathode, a main grid extending along the greater portion of the length of the cathode, an auxiliary grid separate from the main grid and at one end of 80 the main grid and extending along a relatively small portion of the cathode, both of said grids being between the anode and the cathode and out of contact with each.
  9. A radio tube having a cathode, an 85 anode, a resistance heater for the cathode energized from a source of alternating current, a main grid between the anode and cathode extending along the cathode, and an auxiliary grid extending along the cathode beyond one end of the main grid and separate therefrom, and means for impressing a negative potential on said auxiliary grid to thereby eliminate the inductive field produced by alternating currents in the 90 heater.
  10. The method of eliminating alternating current effects in radio tubes having cathodes heated by a resistance element in an alternating current circuit which consists in providing an auxiliary control in the tube and maintaining a negative potential on said auxiliary control element.
  11. A radio tube having an anode, a cathode substantially coextensive with the anode, 105 a looped heater for the cathode having terminals at one end thereof, a helical main control electrode between the cathode and anode, and a helical auxiliary control electrode at one end of the main control electrode and separate therefrom, said auxiliary control electrode being located adjacent the end portion of the cathode and the end portion of the anode.
- In testimony whereof I hereunto affix my 115 signature.

EARL L. KOCH.
